UNITED STATES PATENT OFFICE.

ELMOND C. IMMEL, OF LEERAY, TEXAS.

SLIP SOCKET.

Application filed July 6, 1921. Serial No. 482,656.

To all whom it may concern:

Be it known that I, ELMOND C. IMMEL, a citizen of the United States, residing at Leeray, in the county of Stephens and State of Texas, have invented certain new and useful Improvements in Slip Sockets, of which the following is a specification, reference being had to the accompanying drawings.

This invention relates to slip sockets and has for its object to provide a device of this character whereby the sucker rod, used in well drilling, may be readily withdrawn.

It is also an object of the invention to provide a device of this character wherein the parts may be readily disassembled without destroying their efficiency.

It is another object of the invention to provide a slip socket of this character wherein chuck jaws are used to grip the sucker rod, said chuck jaws being urged outwardly of the body member or socket by a spring so as to cause the jaws to substantially contract and grip the sucker rod.

It is a further object of the invention to provide a device of this character wherein the spring used to urge the chuck jaws into engagement with the sucker rod may be readily compressed to permit ready removal of the chuck jaws.

It is a still further object of the invention to provide a slip socket of this character wherein a plurality of chuck jaws are used and are retained within the socket by means of a cap, disengagement of the jaws from the cap being prevented by the spring.

With these and other objects in view, the invention consists in the improved construction and arrangement of parts to be herein-after more particularly described, fully claimed and illustrated in the accompanying drawings in which:

Figure 1 is a view in elevation of a slip socket constructed in accordance with an embodiment of the invention,

Figure 2 is a longitudinal sectional view,

Figure 3 is a longitudinal sectional view showing the device in use,

Figure 4 is an end elevation of the slip socket,

Figure 5 is a section taken on the line 5-5 of Figure 2,

Figure 6 is a section taken on the line 6-6 of Figure 2,

Figure 7 is a detailed view of the tool used in disassembling the slip socket, and

Figure 8 is a detailed view of the end portion of one of the jaw shanks.

Referring to the drawings, 5 designates a body member having its end 6 reduced and formed into a threaded stem for connection to any suitable implement. The intermediate and opposite end portion 8 of the body member is provided with a bore 9, opposed slots 10 being provided in the side walls of the body member and adapted to communicate with the bore 9. It will be noted that the inner surface of the end 8 of the body member gradually inclines from the intermediate portion of the body member to the extremity of the end 8 to substantially form a cone, the purpose of which will be herein-after described. A supplemental bore 11 is provided in the closed end of the body member, said bore being threaded.

A spring 12 is mounted within the bore 9 and is adapted to engage the end wall 13 of the bore, said spring being greater in diameter than the diameter of the bore 11, so as to surround the edges of said bore. The opposite end of the spring is adapted to receive a supporting member 14, including an extension 15 which is adapted to be disposed within the end of the spring, the member 14 resting upon the end coil of the spring. This member as well as the extension 15 is provided with an opening 16 which is greater in diameter than the bore 11, the purpose of which will be herein-after described.

In order to permit a broken rod to be withdrawn from the bore of the well, there is provided a novel mechanism embodying a cap 17 having a flange 18 and an opening 19. Slots 20 are provided in the head of the cap, one end of each slot communicating with the opening 19. The supporting member 14 is adapted to be disposed within the cap, the opening 19 being considerably larger than the bore 16 so that a socket 21 is formed through the cooperation of the supporting member 14 and the cap, for the reception of a washer 22. In connection with the cap 17, a plurality of chuck jaws 23 are employed, each jaw being substantially segmental in cross section and having its concave face 24 provided with teeth, while its convex face 25 is tapered to conform to the cone shaped end of the bore 9, said tapered portion terminating adjacent the end 26 of the jaw. Formed integral with, and projecting from the end 26 of each jaw is a shank 27, said shank be-

ing considerably longer than the jaw, and having its end portion 28 provided with a pair of opposed recesses 29, said recesses being disposed inwardly of the extremity of 5 said end portion, the shanks 27 being resilient so as to respond to the movement of the jaws outwardly of the socket member and permit said jaws to firmly clamp the sucker rod.

- 10 In assembling the device, the spring 12 is disposed in engagement with the end 13 and over the supplemental bore 11. The supporting member 14 is then positioned upon the opposite end of the spring. The cap 17 is 15 disposed within the bore 9 with the flange 17 extending toward the wall 13. The chuck jaws 23 are then placed within the bore so as to permit the end portions 28 of the shanks 27 to pass through the opening 19 of 20 the cap and permit the reduced portions of said ends formed by the recesses 29 to pass into the slots 20. The member 14 is then permitted to move into the cap so as to close the open ends of the slots and lock the end portions 28 of the shanks to the cap, the expansion of the spring causing the jaw members 23 to move through the cone shaped portion of the bore 9 so as to substantially contract said members and cause the same to 30 grip the desired object.

It is of course obvious that in assembling and disassembling the device the spring will be prevented from expanding. This is accomplished by means of a screw 30 having a threaded shank 31, a flange 32 being formed on one end, and a substantially rectangular head 33 formed above the flange. This screw is adapted to be passed through the chuck jaws 23, the opening 19, and the washer 22, 40 as well as through the bore 16 of the holding member, and into the supplemental bore 11. A suitable wrench 34 is provided, said wrench being adapted to extend through the jaw members 23 so as to engage the head 33 45 of the screw. Upon rotation of the wrench, the screw will be moved into the bore 11 so as to cause the flange 32 to engage the washer 22. The rotation of the screw will cause the holding member 14, together with the spring, 50 to be moved toward the end wall 13, thereby relieving the cap 17 of pressure, as well as opening the slots 20 to permit removal or release of the end portions 28 of the shanks.

It is of course obvious that after the member 14 is withdrawn from the cap 17, the jaws 23 may be readily removed from the socket by passing the same through the slots 10, it being also possible to remove the cap in the same manner. After the various parts 60 of the device have been assembled as above described, the wrench 34 is used to withdraw the screw 30 so as to permit the spring to expand and cause the member 14 to engage

the cap 17 and urge the jaw members 23 toward the end 8 of the body member.

65

From the foregoing it will be readily seen that this invention provides a novel form of slip socket, so constructed that the parts may be readily assembled and disassembled with ease, and wherein a double resilient function 70 is obtained through the cooperation of the shanks 27 of the chuck jaws and the spring 12, and when a sucker rod is once inserted in the bore 9, accidental disengagement is impossible.

75

What is claimed is:

1. A slip socket of the character described comprising a body member, a spring disposed in said body member, a supporting member carried by the spring, a cap engaged 80 with the supporting member, said cap having an opening in its central portion and slots communicating with said opening, and chuck jaws including shanks, said shanks being disposed in the slots of the cap, said 85 chuck jaws and shanks being secured and urged toward one end of the body member through the cooperation of the holding member and the cap.

2. A slip socket of the character described 90 comprising a body member, a spring disposed in said body member, a supporting member carried by the spring, a cap engaged with the supporting member, said cap having an opening in its central portion and 95 slots communicating with said opening, and chuck jaws including shanks, said shanks being disposed in the slots of the cap, said holding member being adapted to extend into the cap to lock the shanks within the 100 slots.

3. A slip socket of the character described comprising a body member having a supplemental threaded bore in one end thereof, a spring disposed in said body member and 105 surrounding the mouth of the supplemental bore, a supporting member carried by the opposite end of the spring, said supporting member having a central bore, a cap supported by the supporting member, said cap having a central opening and a plurality of 110 slots communicating with said opening, chuck jaws disposed within said body member, each of said chuck jaws including a shank having its end portion disposed within one of the slots of the cap, and a screw member arranged to be extended through the opening of the cap into the supplemental bore of the body member for engagement with the supporting member to compress the 115 spring and permit the release of the shanks of the chuck jaws.

In testimony whereof I hereunto affix my signature.

ELMOND C. IMMEL.
